UNITED STATES PATENT OFFICE

149,101

DESIGN FOR A GLOVE

Hilda Woller-Duff, New York, N. Y.

Application August 24, 1946, Serial No. 132,835

Term of patent 3½ years

(Cl. D3—11)

To all whom it may concern:

Be it known that I, Hilda Woller-Duff, a citizen of the United States of America, residing in New York, county of New York, and State of New York, have invented a new, original, and ornamental Design for a Glove, of which the following is a specification, reference being had to the accompanying drawing, forming part thereof.

Fig. 1 is a front perspective view of a glove showing my new design.

Fig. 2 is a rear perspective view thereof.

I claim:

The ornamental design for a glove, substantially as shown.

HILDA WOLLER-DUFF.
